MASS SPECTROMETRY

Harold W. Washburn, Pasadena, Calif., assignor
to Consolidated Engineering Corporation, Pasadena, Calif., a corporation of California

Application November 21, 1944, Serial No. 564,424

7 Claims. (Cl. 250—41.9)

1

This invention is concerned with mass spectrometry and particularly with the analysis of mixtures with a mass spectrometer. It provides improvements in methods and apparatus for mass spectrometry to the end that mass spectra of improved uniformity may be produced, and is a continuation-in-part of my co-pending application Serial No. 513,528, filed December 9, 1943.

The mass spectrometer is adapted for use in both qualitative and quantitative analysis. It has been employed for scientific studies such as the measurement of isotope ratios and, more recently, for other problems such as analysis of complex mixtures of hydrocarbons. It is, essentially, an apparatus for producing ions and sorting them according to the ratio of their mass to their charge, i. e. according to their specific mass. A sample to be analyzed, for example a gas mixture, is ionized in a chamber, for example by heating or by electron bombardment, and the resulting ions are propelled by an electrical field through an aperture into an analyzer. There the ions, under the influence of a magnetic or electric field are sorted in accordance to their specific mass, ions of low specific mass pursuing a path different from those of high specific mass. The sorted ions are collected and discharged, the quantity of each kind of ions being measured by the amount of current that they discharge upon collection.

In one type of mass spectrometer, ionization is accomplished by bombarding molecules of the sample in an ionization chamber with a beam or stream of electrons, and the resulting ions are forced through an ion outlet aperture in a first electrode by means of an electrical field produced by impressing a potential across the region in which the ions are produced from a pusher electrode to the first electrode. The beam of ions passing through the aperture in the first electrode may be further focussed or collimated by passing it through an aperture in a second electrode, the beam being propelled through the aperture in the second electrode by means of a potential impressed across the space between the first and second electrodes.

In a preferred form of this type of mass spectrometer, the first and second electrodes have ion slits that are elongated in cross-section and disposed substantially in line, i. e. oriented with each other. Means are provided for directing an electron beam through the space between the pusher electrode and the first electrode, preferably substantially parallel to the two slits or at least in the plane defined by the two slits. In this form of apparatus ions are formed in the space between the pusher and first electrode and collimated into an ion beam or ribbon which passes through the slits into the analyzer of the apparatus.

2

I have discovered that the sensitivity and stability of the spectrometer can be increased markedly with the result that spectra of improved intensity and stability can be produced, if the voltage which is employed to force the ions as a beam through the two collimating slits or apertures has a component in a direction transverse to the axis of the apertures. By altering the magnitude of this transverse component, it is possible to obtain a spectrum of maximum intensity.

The "crossed field" or transverse component can also be adjusted to counteract so-called surface effects, such for example as those produced by vagrant ions which charge insulating surfaces which may be formed by deposits on the walls of the ionization chamber and which tend to introduce irregularities and errors in the spectrum. Thus, the use of the invention makes possible an improvement in the consistency of results obtained with the spectrometer.

The "crossed field" has further advantages in that:

1. The transverse component can be adjusted to select ions originating in the uniform part of the electron beam;
2. The adjustment can be used to ascertain that the ions are being selected from the uniform part of the beam;
3. The apparatus can be so set that small changes in focussing of the ion beam will not affect recorded beam intensity, so that spectra of improved uniformity and intensity are obtained.
35. Moreover, during the course of an analysis in which peaks which represent the amounts of ions of different specific mass are produced successively on a record, the transverse component may be changed from time to time so that each successive peak is reproduced at maximum intensity.

As disclosed in the aforementioned copending application, one way of providing a propelling or accelerating voltage with a transverse component for the ions in the region in which the beam is formed is to employ a plurality of pusher electrodes together with means for impressing different potentials between the respective pusher electrodes and the first electrode. In this way the ions are subjected to a voltage which has a component in a direction transverse to the axis of the aperture in the first electrode and by adjusting the potentials at the several pusher electrodes, this transverse component may be altered to obtain a mass spectrum of maximum intensity.

55. In accordance with the instant invention, a transverse component for the accelerating voltage is provided in another way, which is particularly applicable in the case of an apparatus in which the ion slits are elongated in cross-section. Thus, I provide at least one auxiliary to

cussing electrode mounted between the first and second electrodes (which contain the slits) adjacent the end of the slits and also providing means for impressing a potential on the auxiliary electrode to affect the focussing of ions passing through the space between the slits. In this way the ion beam formed when the ions pass through the slits may be adjusted, particularly with respect to the width. Thus, the invention may be utilized to avoid undesirable spreading of the ion beam. Accordingly, my invention contemplates in a mass spectrometer having an ionization chamber provided with a first electrode having an ion outlet slit that is elongated in cross-section, and means for propelling ions through the slit, the combination which comprises a second electrode disposed outside the chamber and provided with an elongated ion outlet slit disposed substantially in line with that of the first electrode, means for impressing a potential between the first and second electrode to propel ions issuing from the chamber through the slit in the second electrode, at least one auxiliary focussing electrode mounted between the first and second electrodes adjacent an end of a slit, means for impressing a potential on the auxiliary electrode to affect the focussing of ions passing through the space between the slits, means for introducing molecules into the ionization chamber, and means for directing an electron beam against the molecules in the chamber.

In the preferred form of the apparatus of my invention a plurality of auxiliary focussing electrodes are provided, these being mounted opposite each other between the first and second electrodes adjacent the ends of the slits and on opposite sides of the beam.

In a further modification of my invention, a third electrode is disposed beyond the second electrode and has a slit of elongated cross-section in line with the other two slits. A second set of auxiliary electrodes is mounted so that the electrodes are opposite each other between the second and third electrodes adjacent the sides of the ion beam and means are provided for impressing a potential between the second set of auxiliary electrodes to affect the focussing of the beam in this region. When three slotted electrodes are employed, the second set of auxiliary electrodes should be so disposed that a line drawn between them makes a different angle with the beam than that made by a line drawn between the first set of auxiliary electrodes.

The apparatus of the invention preferably is mounted within a magnetic field, i. e. means should be provided for creating a magnetic field in the space which includes the slits. In some instances this means will be the magnet which exerts its influence on the analyzer of the apparatus.

These and other features of my invention will be understood more thoroughly in the light of the following detailed description taken in conjunction with the accompanying drawings in which:

Fig. 1 is a schematic diagram of an ionization chamber adapted for the practice of my invention and including two collimating or slit electrodes with a set of auxiliary or focussing electrodes disposed therebetween;

Figs. 2 and 3 are longitudinal sectional views through a preferred form of the ionization chamber of Fig. 1, the sections being taken at right-angles to each other;

Fig. 4 is a wiring diagram of apparatus adapted to change the ratio of voltages applied to the two auxiliary or focussing electrodes of the apparatus of Figs. 1 to 3, during the recording of a mass spectrum with such apparatus; and

Fig. 5 is a schematic diagram of the ionization chamber of a mass spectrometer adapted for the practice of my invention and provided with three slit or collimating electrodes with a first set of focussing electrodes between the first and second slit electrodes and with the second set of focussing electrodes between the second and third slit electrodes.

Referring now to Fig. 1, it will be observed that the instrument comprises an ionization chamber 10 disposed adjacent an analyzer tube 11 which is followed by a conventional ion collector (not shown), all disposed within an envelope 14 that is adapted to be maintained at low pressure by pumps (not shown). A gas sample to be analyzed may be introduced into the ionization chamber through an inlet conduit 16 which passes through the envelope wall at one end thereof.

Molecules of the gas sample are converted into ions in the ionization chamber by being bombarded with electrons of an electron beam 17 which is shot across the ionization chamber from an electron gun 17A to an electron catcher 17B. The ions thus formed are moved toward a slit S₁ in a first propelling electrode 18 by means of a potential imposed across the gap between this electrode and pusher electrode P₁, disposed within the ionization chamber.

The electron beam passes through the space between the first propelling electrode and the pusher electrode and parallel to the slit S₁ in the first propelling electrode.

As the result of the potential impressed between the pusher electrode and the first propelling electrode the ions pass through the slit S₁ with substantial velocity. The ions are further accelerated at this point by an additional potential impressed between the first propelling electrode and a second propelling electrode 19 having a slit S₂ parallel to the first slit S₁. The two slits act as a collimator and cause the ions to be projected into the analyzer tube as a narrow beam or ribbon. This beam is caused to follow a curved path in the analyzer tube due to the presence of a strong magnetic field impressed by an electromagnet (not shown). The magnetic field has another effect in that it causes the heterogeneous ion beam that passes through the slits S₁, S₂ to be separated in the analyzer into a plurality of separate diverging ion beams according to the specific mass of the ions. By varying the accelerating potential or the magnetic field, or both, each of the ion beams may be caused to focus at the outlet slit of the analyzer tube, so that the ions of this beam impinge upon the ion collector and are there discharged. The resulting current is amplified and recorded to produce the mass spectrum of the gas being analyzed.

The apparatus of Fig. 1 is provided with a pair of auxiliary or focussing electrodes A₁, A₂ disposed between the two collimating electrodes adjacent the edges of the ion beam. By separately energizing these auxiliary electrodes and by impressing different potentials upon the two, the ion beam or ribbon may be focussed, i. e. expanded or contracted in the region between the two collimating electrodes. In this way a transverse component of the voltages is created and it is this

transverse component which affects the focusing. The transverse component may be varied at will to minimize changes in sensitivity that result from changes in focus of the ion beams due to surface changes, etc., built up within the instrument by vagrant ions.

In the apparatus of Fig. 1, a battery or other constant voltage supply 30 is provided and is connected to the ends of a potentiometer 32. The positive end of this potentiometer and its slider are connected through a switch 36 to a condenser 34. A potential divider circuit is connected across this condenser and takes the form of a resistor 38 connected in series with two other series resistors or potentiometers, 39, 40, which are in parallel with each other and are in turn connected in series with a fourth resistor 41. The negative end of the potential dividing network is connected to ground. The pusher electrode P_1 is connected to the positive side of the network, i. e. to the upper end of the resistor 38 in Fig. 1. The first collimating electrode 18 is connected to the other end of the resistor 38. One of the auxiliary or focussing electrodes A_1 is connected as the slider of a potentiometer on the resistor 39, the other auxiliary electrode A_2 being connected to the slider on the resistor or potentiometer 40. The second propelling or collimating electrode 19 is connected to the negative end of the network and to ground.

If the potential across the condenser changes, the potentials on the electrodes connected thereto will change proportionally. Similarly shifting of the sliders of the potentiometers 39, 40 will change the ratio of the potentials applied to the focussing electrodes A_1 , A_2 . In the operation of the apparatus the sliders on the potentiometers 39, 40 are shifted to produce maximum intensity for the particular peak of the spectrum being measured.

A preferred form of ionization chamber of my invention is shown in Figs. 2 and 3. Referring to these figures, it will be observed that the apparatus comprises a cylindrical head 50, the rear of which connects with the gas sample inlet conduit 16. Within the head there is an extension of this conduit in the form of gas passages 51, 52 which are enclosed by conductors 53, 54 that terminate in the pusher electrode P_1 . This pusher electrode is spaced from the first propelling electrode 18 which is provided with the slit S_1 . An electron beam is projected in the space between the pusher electrode and the first propelling electrode and substantially parallel to the slit in the latter from an electron gun 55 mounted outside the head and connected with the ionization chamber through an aperture or window 56. The other propelling electrode 19 provided with the slit S_2 is disposed parallel to the first propelling electrode but spaced therefrom. The slits S_1 and S_2 are parallel with each other and with the electron beam. The head of the ionization chamber is fastened to the adjacent analyzer tube 11 by means of a flange.

The auxiliary or focussing electrodes A_1 , A_2 are mounted within the ionization chamber between the slit electrodes 18, 19 and are insulated therefrom. The auxiliary electrodes are thus disposed adjacent the ends of the slits and work upon the edges of the electron beam or ribbon formed as the ions pass through the slits S_1 , S_2 . In many instances it is desirable to change the ratio of the voltages applied to the two auxiliary electrodes during the recording of a mass spectrum since a different ratio may be optimum for each peak. One circuit arrangement for accomplishing this

result during the automatic recording of a mass spectrum is illustrated in Fig. 4 which is similar to the wiring diagram of Fig. 1 except that potentiometers 60, 62 are connected respectively in series with the leads to the auxiliary electrodes A_1 , A_2 . These two potentiometers introduce constant voltages V_1 , V_2 into the leads to the auxiliary electrodes. To automatically record a mass spectrum, the condenser 34 is charged to a high potential by closing the switch 36. When this switch is open, the condenser gradually discharges through the potential divider circuit including the resistance 38, the potentiometers 39, 40 and the resistance 41. While a condenser is thus discharging, beams comprising ions of lower and lower specific mass fall successively on the collector (not shown). Simultaneously, the transverse voltage component introduced by the electrodes A_1 , A_2 varies. By suitably adjusting the potentiometers 60, 62 as well as the potentiometers 39, 40 the ratio of the various propelling voltages as a function of specific mass may be varied in a wide variety of ways. By suitable settings of those potentiometers, the optimum operating point for ions of each specific mass may be obtained.

Referring now to Fig. 5, it will be observed that the ionization chamber and the wiring diagram of this apparatus are the same as that of Fig. 1, like parts being identified by like reference numbers and letters except in the following particulars:

The ionization chamber is provided with an additional collimating electrode 100 disposed beyond the collimating electrode 19 and parallel thereto. This third collimating electrode has an elongated slit S_3 parallel to slits S_1 , S_2 . The second pair of focussing electrodes A_3 , A_4 is disposed between the second collimating electrode 19 and the third collimating electrode 100. This second pair of auxiliary electrodes, instead of being disposed adjacent the edges of the ion beam as are A_1 , A_2 , are disposed at right angles thereto and work upon the thin section of the ion beam or ribbon. This second pair of focussing electrodes likewise aids in focussing and collimating the electron beam.

The wiring diagram of Fig. 5, as indicated above, is similar to that of Fig. 1 except that it is provided with another pair of potentiometers 101, 102 connected in series in the potential dividing network, but in parallel with each other. The slider of the potentiometer 101 is connected to auxiliary electrode A_4 and the slider of the potentiometer 102 is connected to the auxiliary electrode A_3 . By adjusting the potentials applied to the second set of auxiliary electrodes with the second set of potentiometers, the focussing of the beam may be affected.

In operation, the settings of the potentiometers 39, 40 and of the potentiometers 101, 102 are adjusted to give maximum sensitivity.

In many instances it is desirable to change the ratio of pusher voltage, i. e. the ratio of the voltages applied to the two pusher electrodes during the recording of a mass spectrum, since a different ratio may be optimum for each peak.

I claim:

1. In a mass spectrometer having an ionization chamber provided with a first electrode having an ion outlet slit that is elongated in cross-section, and means for propelling ions through the slit, the combination which comprises a second electrode disposed outside the chamber and provided with an elongated ion outlet slit dis-

posed substantially in line with that of the first electrode, means for impressing a potential between the first and second electrode to propel ions issuing from the chamber through the slit in the second electrode, at least one auxiliary focussing electrode mounted between the first and second electrodes adjacent an end of a slit, means for impressing a potential on the auxiliary electrode to affect the focussing of ions passing through the space between the slits, means for introducing molecules into the ionization chamber, and means for directing an electron beam against the molecules in the chamber.

2. In a mass spectrometer having an ionization chamber provided with a first electrode having an ion outlet slit that is elongated in cross-section, and means for propelling ions through the slit, the combination which comprises a second electrode disposed outside the chamber and provided with an ion outlet slit elongated in cross-section and disposed substantially in line with that of the first electrode, means for impressing a potential between the first and second electrode to propel ions issuing from the chamber as a beam through the slit in the second electrode, auxiliary focussing electrodes mounted opposite each other between the first and second electrodes adjacent the ends of the slits and on opposite sides of the beam, means for impressing a potential on the auxiliary electrodes to affect the focussing of ions passing through the space between the slits, means for introducing molecules into the ionization chamber, and means for directing an electron beam against the molecules in the chamber to form the ions.

3. In a mass spectrometer having an ionization chamber provided with a first electrode having an ion outlet slit that is elongated in cross-section, and means for propelling ions through the slit, the combination which comprises a second electrode disposed outside the chamber and provided with an ion outlet slit elongated in cross-section and disposed substantially in line with that of the first electrode, means for impressing a potential between the first and second electrode to propel ions issuing from the chamber as a beam through the slit in the second electrode, auxiliary focussing electrodes mounted opposite each other on the two sides of the beam between the first and second electrodes adjacent the ends of the slits, means for impressing a potential between the auxiliary electrodes to affect the focussing of ions passing through the space between the slits, a third electrode disposed beyond the second electrode and having a slit of elongated cross-section in line with the other two slits, a second set of auxiliary electrodes mounted opposite each other between the second and third electrodes adjacent the sides of the ion beam, means for impressing a potential between the second set of auxiliary electrodes to affect the focussing of the beam between the slits in the second and third electrodes, means for introducing molecules into the ionization chamber, and means for directing an electron beam against the molecules in the chamber.

4. In a mass spectrometer having an ionization chamber provided with a first electrode having an ion outlet slit, and means for propelling ions through the slit, the combination which comprises a second electrode disposed outside the chamber and provided with an ion outlet slit disposed substantially in line with that of the first electrode, means for impressing a potential

5 between the first and second electrode to propel ions issuing from the chamber as a beam through the slit in the second electrode, auxiliary focussing electrodes mounted between the first and second electrodes on opposite sides of the beam, means for impressing a potential between the auxiliary electrodes to affect the focussing of ions passing through the space between the slits, a third electrode mounted beyond the second electrode with a slit disposed in line with those in the first and second electrode and in the path of the beam, another set of auxiliary electrodes mounted between the second and third electrodes on opposite sides of the beam and at a different angle to the beam than the angle made by the first auxiliary electrodes, means for impressing a potential between the auxiliary electrodes of the second set, means for introducing molecules into the ionization chamber, and means for directing an electron beam against the molecules in the chamber.

ends of said slits, means for impressing a potential between the first and second electrodes to propel ions issuing from the chamber as a beam through the slit in the second electrode, means for impressing a potential between the second and third electrodes for accelerating the ion beam passing therebetween, means for impressing an adjustable potential on the first pair of focusing electrodes, means for impressing an adjustable potential on the second pair of electrodes, the means for impressing the adjustable potentials on the two pairs of electrodes being independent of the means for adjusting the potential impressed on said first, second and third electrodes, and means associated with said potential impressing means for proportionately varying the potential on all of said electrodes.

HAROLD W. WASHBURN.
